UNITED STATES PATENT OFFICE

WILLIAM H. TAYLOR, OF BEAUMONT, TEXAS.

SET SHOE.

Application filed March 13, 1923. Serial No. 624,795.

To all whom it may concern:

Be it known that I, WILLIAM H. TAYLOR, a citizen of the United States, residing at Beaumont, in the county of Jefferson and State of Texas, have invented certain new and useful Improvements in Set Shoes, of which the following is a specification.

This invention is an appliance used in connection with oil-well drilling operations, and more particularly after the well has been drilled into the oil-bearing stratum, and it is desired to clean the screen at the bottom of the hole, so as to allow the oil to properly enter the same.

15 The invention has for its object to provide a very efficient and reliable appliance for the purpose stated, and also one which is easy to handle and simple in construction.

20 With the object stated in view, the invention consists of a set-shoe embodying a novel combination and arrangement of parts to be hereinafter described and claimed, and in order that the same may be better understood, reference is had to the accompanying drawing, wherein,—

25 Figure 1 is an elevation of the appliance; Figs. 2 and 3 are enlarged vertical sections of the set-shoe showing the same in different positions, and Fig. 4 is a sectional detail on the line 4—4 of Fig. 2.

Referring specifically to the drawing, 10 denotes a fragment of a well casing which is set in the hole, and which encloses a discharge tube 11 extending to the top of the well. The hole is contracted below the bottom of the casing to form an annular shoulder on which seats the set-shoe 12 fitted to the bottom of the casing. To the lower end 40 of the tube 11 is connected a strainer 13 which may be a perforated tube. The lower contracted end of the hole extends into the oil sand or other oil-bearing stratum or formation, and the strainer 13 is located in this portion of the bore so that the oil may enter the strainer and be carried to the surface of the ground by the tube 11.

50 To the bottom of the strainer 13 is fitted the set shoe which is the subject matter of the present application for patent. This shoe is composed of a pair of slidably connected tubular sections 14 and 15 open at their ends. To the top of the upper section 14 is connected a nipple 16, which lat-

ter, in turn, is connected to the bottom of the strainer 13 by an ordinary coupling sleeve 17. The bottom section 15 is adapted to seat on the bottom of the contracted portion of the well hole or bore.

In the section 14, near the lower end 60 thereof, is rigidly mounted a valve seat composed of a ring 18, the central opening 19 of which forms a port establishing communication between the sections 14 and 15. Above this valve seat, the section 14 also 65 contains an ordinary back-pressure valve 20.

The upper portion of the section 15 extends into the section 14, and is here fitted with a valve 21 adapted to close the opening 19. This valve has the shape of a cap, 70 its top being tapered so as to fit in the port 19, and the top of the cap has side ports 22, through which and the port 19 communication is established between the sections 14 and 15 when the valve is not seated 75 and closing the port 19.

The section 14 has a number of longitudinal side slots 23 into which loosely extend guide screws or pins 24 carried by the section 15, whereby the section 15 is 80 prevented from rotating relative to the section 14, but is free to slide to the extent of the length of the slots. The screws or pins 24 also prevent endwise separation of the sections 14 and 15.

85 The section 15 is normally held stationary in lowered position relative to the section 14 by means of one or more readily frangible coupling pins 25 passing through said sections, and with the parts in this position, the appliance is ready to be lowered into the well for operation. When the bottom of the well is reached, the appliance will be slightly raised so as to leave the lower section 15 of the set shoe clear of the bottom of the well. The outside of the strainer 13 can now be washed by means of water pumped to the bottom of the well by an ordinary wash pipe which is lowered down the tube 11 and through the strainer 13 until its lower end is within a few inches of the section 14. The circulating water pump is then started, whereupon the water is pumped through the sections 14 and 15 to escape from the bottom of the lower section and pass upwardly along the outside of the strainer. The valve 21 being unseated the water passes freely 100 from the section 14 into the section 15 by

the way of the ports 19 and 22. After the strainer has been thoroughly washed, the appliance is lowered to the bottom of the hole and slightly jarred whereupon the impact of the section 15 with the bottom of the hole causes the pins 25 to be sheared off, thereby uncoupling the sections 14 and 15 so that the weight of the section 14 and the parts above carrying the same causes said section to descend to bring the port 19 over the valve 21. As the port 19 is now closed and the section 15 is seating on the bottom of the hole and therefore closed at this point, the water cannot escape, which causes the circulating pump to choke, thereby notifying the driller that the inlet to the strainer by the way of the bottom thereof is tightly closed, and that nothing can enter the strainer except through the perforations thereof.

20 In setting a screen in a well fitted with a back pressure valve used in an ordinary set shoe or coupling, it is impossible to tell whether or not the valve has closed after the screen is washed, because a valve of this kind is held to its seat by a spring. However, with the use of the present appliance the seating of the valve is made apparent to the driller without fail because it is held against its seat by the weight of the strainer, and the parts above the same, and the entire weight is then carried by the point of contact between the valve 21 and its seat 18.

I claim:

- 35 The combination with a well-strainer and a discharge tube to which the same is connected; of a set-shoe connected to the bottom of the strainer, said shoe consisting of upper and lower sections connected for a relative sliding movement, frangible coupling means locking the sections against such movement, a valve in one of the sections, and a seat for the valve in the other section, said valve being open when the sections are locked, and closing by the relative sliding movement thereof.
- 40 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.
- 45 The combination with a well-strainer and a discharge tube to which the same is connected; of a set-shoe connected to the bottom of the strainer, said shoe consisting of upper and lower sections connected for a relative sliding movement, frangible coupling means locking the sections against such movement, and coacting means associated with the sections for preventing a flow of fluid therethrough, said means being in inoperative position when the sections are locked and being placed in operative position by the relative sliding movement thereof.
- 50 The combination with a well-strainer and a discharge tube to which the same is connected; of a set-shoe connected to the bottom of the strainer, said shoe consisting of upper and lower sections connected for a relative sliding movement, frangible coupling means locking the sections against such movement, and coacting means associated with the sections for preventing a flow of fluid therethrough, said means being normally in inoperative position when the sections are locked and being placed in operative position by the relative sliding movement thereof.
- 55 The combination with a well-strainer and a discharge tube to which the same is connected; of a set-shoe connected to the bottom of the strainer, said shoe consisting of upper and lower tubular sections open at their ends, and connected for a relative sliding movement, frangible coupling means

locking the sections against such movement, and coacting means associated with the sections for preventing a flow of fluid therethrough, said means being in inoperative position when the sections are locked and being placed in operative position by the relative sliding movement thereof.

60 The combination with a well-strainer and a discharge tube to which the same is connected; of a set-shoe connected to the bottom of the strainer, said shoe consisting of upper and lower tubular sections open at their ends, and connected for a relative sliding movement, frangible coupling means locking the sections against such movement, a valve in one of the sections, and a seat for the valve in the other section, said valve being open when the sections are locked, and closing by the relative sliding movement thereof.

65 The combination with a well-strainer and a discharge tube to which the same is connected; of a set-shoe connected to the bottom of the strainer, said shoe consisting of upper and lower tubular sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

70 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve in one of the sections, and a seat for the valve in the other section, said valve being open when the sections are locked, and closing by the relative sliding movement thereof.

75 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

80 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

85 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

90 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

95 The combination with a well-strainer and a discharge tube to which the same is connected; of a set-shoe connected to the bottom of the strainer, said shoe consisting of upper and lower sections open at their ends, and connected for a relative sliding movement, frangible coupling means locking the sections against such movement, a valve seat ring in the upper section, and a valve in the lower section for said seat, said valve being in unseated position when the sections are locked, and seating by the relative sliding movement thereof.

100 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

105 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

110 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

115 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

120 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

125 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

130 The combination with a well-strainer and a discharge tube to which the same is connected; of a set-shoe connected to the bottom of the strainer, said shoe consisting of upper and lower sections connected for a relative sliding movement, and coacting means associated with the sections for preventing a flow of fluid therethrough, said means being normally in inoperative position, and being placed in operative position by the relative sliding movement of the sections.

bottom of the strainer and consisting of upper and lower sections connected for a relative sliding movement, frangible coupling means locking the sections against such movement, the lower section being adapted to seat on the bottom of the well hole to permit the upper section to slide downwardly relative to said seated section when

the coupling means is broken, a valve in one of the sections, and a seat for the valve in ¹⁰ the other section, said valve being open when the sections are locked, and closing when the upper section slides downwardly.

In testimony whereof I affix my signature.

WILLIAM H. TAYLOR.
